(57) **CLAIM**

The ornamental design for a shoe sole, as shown and described.

DESCRIPTION

FIG. 1 is a lateral side view of a shoe sole showing our new design;

FIG. 2 is a first lateral perspective view thereof;

FIG. 3 is a second lateral perspective view thereof;

FIG. 4 is a third lateral perspective view thereof;

FIG. 5 is a fourth lateral perspective view thereof; and,

FIG. 6 is a top view thereof.

The dash-dot-dash broken lines immediately adjacent the photographic areas represent unclaimed boundaries of the design. The dash-dash-dash broken lines form no part of the claimed design.
